UNITED STATES PATENT OFFICE.

JAMES CULTON, OF DENVER, COLORADO.

MOVEMENT-CONTROLLING MECHANISM FOR POWER-DRIVEN VEHICLES.

1,241,711.

Specification of Letters Patent.

Patented Oct. 2, 1917.

Application filed July 20, 1915. Serial No. 40,898.

To all whom it may concern:

Be it known that I, JAMES CULTON, citizen of the United States, residing at Denver, in the county of Denver and State of Colorado, have invented certain new and useful Improvements in Movement-Controlling Mechanism for Power-Driven Vehicles, of which the following is a specification.

My invention relates to mechanism for automatically controlling the movement of power driven vehicles, and it appertains more particularly to improvements in a system of the character shown and described in my application for Patent No. 795,046, filed October 14, 1913, in which elements respectively positioned adjacent a railway track and carried on a power driven vehicle moving on said track, coöperate to automatically stop the vehicle by action upon the propelling and brake mechanisms of the same.

The primary object of the present invention is to provide in a system of the character described, means which operate to reduce the air pressure in the brake system of a locomotive or other power driven vehicle, gradually, thereby effecting a slow application of the brakes until the vehicle is brought to a stop.

Accidents and damage to the rolling stock likely to occur when the vehicle is brought to a sudden stop are thus averted and in case the control of the locomotive ceases to be dependent on human agency, the motion of the vehicle when approaching a point of danger will be automatically arrested in the same practical manner as though the vehicle were controlled by a careful and able engineer.

Principal among the coöperative means by which this object is accomplished are a series of obstructive devices positioned along the track, an element mounted on the vehicle to control the automatic operation of the propelling and brake mechanisms of the same, and an operating medium intermediate of the track devices and the controller element for translating its contact with the one into effective operations of the other.

Key-controlled means are provided to place the operating medium of either an effective or ineffective condition and a register coöperatively associated with the me-

dium records automatically the periods during which it is in an effective condition and the points of time at which it produces by contact with the track devices, certain determinate actions of the controller element.

Another object of my invention is to provide in coöperative connection with parts of the system for controlling the movement of the vehicle by the influence of the track devices, a governor which produces an effect upon the movement controlling mechanism of the vehicle similar to that hereinbefore described, when the speed of the latter exceeds a predetermined limit. In connection with the elements which automatically control the movement of the vehicle, is provided an indicator for denoting by visual or audible signals, the different actions that take place in the operation of the system.

Further objects of my invention will fully appear in the course of the following description in which reference is had to the accompanying drawings in which the different elements included in my improved system are shown in their preferred form and in coöperative relation to each other and the vehicle to which they are applied.

In the drawings in the various views of which like parts are similarly designated,

Figure 1 is a side elevation of a locomotive to which my invention is applied,

Fig. 2, an end view of the same.

Fig. 3, an enlarged, partially sectional view of the controller element carried on the vehicle,

Fig. 4, a section taken along the line 4—4, Fig. 3 drawn to an enlarged scale,

Fig. 5 an enlarged sectional view of the movable member of the controller element shown in Fig. 3,

Fig. 6, a view similar to Fig. 5, showing the member in its effective condition.

Fig. 7, a partially sectional view of the indicator which denotes the different actions that take place in the operation of the system,

Fig. 8, a section taken along the line 8—8, Fig. 5,

Fig. 9, a section along the line 9—9, Fig. 5,

Fig. 10, a section taken along the line 10—10, Fig. 9, looking in the direction of the arrow drawn across said line,

Fig. 11, a side elevation of a railroad track showing the relative positions of the devices which effect the operation of the controller element on a vehicle moving along the track,

Fig. 12, an enlarged fragmentary view of the working end of the pencil holder included in the register of the movable member of the controller element,

Fig. 13, a longitudinal section of one of the cylinders included in the indicator shown in Fig. 7, drawn to an enlarged scale,

Fig. 14, an elevation of the governor included in the system in association with a diagrammatic representation of the system of pipe connections and valves with which it cooperates, and

Fig. 15, a section taken along the line 20 15-15, Fig. 3.

Referring more specifically to the drawings, the reference numeral 2 designates a railroad track alongside of which are positioned at regular distances apart, the devices 25 3 which effect the operation of the controller element on the vehicle by contact with an operating medium which acts intermediate.

The specific construction of the track devices has been fully shown and described in my copending application for Patent No. 40,899 it being sufficient for the purposes of the present description to state that they each include a curved rail 4 which when engaged by a contact member of the operating medium, compels the same to ride to an elevation determined by its apex and to thereby effect an operative movement of the part of the medium which is in operative connection with the controller element hereinafter to be described.

The rails of the track devices are mounted so that the elevations of their apexes increase progressively from the first to the 45 last of the series of devices with relation to the direction in which the vehicle moves along the track.

My system for the automatic control of the movement of a vehicle moving along a 50 railroad track is of particular value in so-called block systems to prevent the vehicle from passing by inadvertence or disability of its driver, a track signal set at danger.

The series of track devices are in a system 55 of this character, positioned at regular intervals forward of the point at which the semaphore 5 is located, with relation to the predetermined direction in which vehicles move along the track.

60 The track devices may be operatively connected with the semaphore whereby they are placed in an effective condition only when the semaphore is set at danger as will appear in the copending application for patent 65 hereinbefore referred to.

The controller element of the system of co-operative appliances which is carried on the locomotive shown in Fig. 1, comprises a body member 6 upon which the different controlling devices are mounted, and a movable member 7 which forms part of the operating medium hereinbefore referred to.

The member 7 is vertically slidably mounted in a guide-way 8 of the body member and it is at its lower end pivotally connected with a lever 9 which constitutes the other part of the operating medium.

The lever is fulcrumed at one side of the point at which it is pivotally connected with the member 7, in a bearing on the vehicle, as at 10, and it carries at the opposite side of the same, a contact member of suitable construction such as the wheel 12 shown in the drawings, to engage with the treads of the rails 4 of the track devices 3.

The lever has adjacent the point at which it carries the contact member 12, a pin 13 which travels in a segmental slot of a guide-bar 14 suspended from the vehicle, and which engages a spring 15 coiled around said bar which serves to return the lever and the slide member 7 which conjointly constitute the operating medium to their normal positions after they have been lifted by contact of the wheel with the rail of one of the 95 track devices.

The movable member of the controller element consists of a case which is loosely fitted in the guide way 8 and which is provided at opposite sides with ribs 16 slidably disposed in grooves 17 in the sides of the guide way.

The case is divided by means of a horizontal partition 18 into two compartments 19 and 20, the lower one of which contains the 105 key-controlled parts which during the operative movement of the member 7, engage controlling devices on the body member 6.

The parts above mentioned consist of a pair of aligned slidably mounted bolts 21 and 22 which normally are positioned within the compartment 19 as shown in Fig. 5, and which by the operation of a suitable lock mechanism may be laterally projected from the member as illustrated in Fig. 6.

110 The bolts are with this purpose in view, provided with racks 23 which mesh with an interposed pinion 24 on a rotary barrel 25 which is adapted to receive a key 26 inserted through a hole in the front of the 120 case.

To lock the bolts in either their projecting or retracted positions, a pair of pivoted, spring-held slotted tumblers 27 are provided. These tumblers are, as best shown 125 in Fig. 10 of the drawings, provided with registering triangular openings 28 disposed to receive the end of the key protruding through the barrel 25, and they have at the ends of their longitudinal slots 29, notches 130

30 to receive pins 31 projecting rearwardly from the bolts 21 and 22.

When by rotation of the barrel by means of a key inserted in a hole in the front of the case, the bolts are moved to either their protruding or retracted position, the tumblers are first of all moved about their pivots 32 against the retaining action of their springs 33 by the engagement of the end of the key 10 with the sides of the triangular openings 28.

The pivotal movement of the tumblers separates the notches 30 from the respective pins 31 on the bolts and permits the latter to travel through the slots 29 of the tumblers 15 until they reach the opposite ends thereof when they will enter the notches at the said ends and thereby lock the bolts in their adjustable position.

In this connection I desire it understood 20 that the lock above described, merely illustrates a convenient method of adjusting the bolts and locking them in their adjusted positions, and that any suitable locking mechanism controlled by either a key or a dial, 25 may be employed within the spirit of my invention.

The bolts 21 and 22 carry at their extremities downwardly extending arms 34 which serve to hold the controlling devices 30 on the body member in their adjusted positions as will hereinafter be more fully explained.

When the bolts are retracted within the compartment 19 of the slide member 7, the 35 operating medium of which the said member forms part is ineffective, or in other words, the sliding member of the controller element can be moved up and downwardly without effecting the position of the controlling devices on the body member.

When the bolts are by means of the key 26 moved to their projected position, the operating medium will be in its effective condition and during its upward movement 40 will by contact of the bolts, change the position of the movable controlling devices which extend in their paths.

In the upper compartment 20 of the member 7 is a register which records the periods 50 during which the operating medium is in its effective condition, or in other words, the periods during which the bolts 21 and 22 are in their projected position.

The body portion of the controlling element has at one side of its guide-way in 55 which the member 7 has its sliding movement, a channel 35 provided with three branches 36, 37, and 38 which connect respectively with a pipe 39 leading to an air reservoir 40 on the vehicle, a pipe 41 which connects with the sand box 42 on the locomotive, and a pipe 43 which connects with an appliance for operating the throttle of the engine by fluid pressure, which will 60 hereinafter be described.

The flow of air through the channel 38 is controlled by means of two normally closed valves 44 and 45 located respectively at a point between the branches 36 and 37 which connect with the reservoir and the sand box, 70 and at a point between the last-mentioned branch and that which connects with the throttle operating appliance.

The stems of these valves are each provided with oppositely projecting arms 46 75 and 47 one of which extends normally in the path of the bolt 21 on the operating medium.

Each of the valve stems has furthermore, exteriorly of the body-member 6, a cam 155 80 provided with two flat faces which by engagement with a spring 156 retains the respective valve in its adjusted position.

The body member of the controller element is provided at the opposite side of its 85 guide-way with a system of devices for the gradual reduction of the pressure in the conduits of the air brake system of the locomotive, one of which has been designated in the drawings by the numeral 48. 90

The pressure reducing system comprises a series of pressure regulating units placed in vertical succession to be operated successively by means of the projecting bolt 22 on the sliding member when the latter is raised 95 to different elevations by the contact of the wheel 12 on the lever 9 with the series of track devices hereinbefore described.

Each of the pressure regulating units operates to reduce the pressure of air in the 100 air brake system to a predetermined degree of density, so that when the series of units are successively actuated by the action of the operating medium, the pressure in the brake system is gradually reduced 105 until when the upper one of the units has been actuated, the pressure is reduced to the minimum degree required to set the brakes.

The last-mentioned unit is actuated only 110 when in case of an emergency it is necessary to automatically stop the motion of the engine before it reaches a given point on the track and the unit will for this reason be referred to in the following part of the 115 description as the "emergency unit" of the series.

The body member 6 of the controller element has for the application of the pressure reducing system, a passage 49 preferably 120 divided into two communicating compartments by a partition 50.

The chamber is connected at a point 51 with the conduit 48 of the air brake system and it is by means of ducts 52 connected at 125 vertically successive points with valve chambers 53 which are formed in the body member equidistantly in a line substantially parallel to the passage 49.

Each of the pressure regulating units 130

which in their entirety are designated by the numerals 60, 61, 62 and 63, consists as best shown in Fig. 4 of the drawings, of two coöperative members one of which is 5 operated by the action of the sliding member to establish communication between the respective valve chamber 53 and the passage 49, by opening the respective connection 52, and the other one of which acts to subsequently 10 interrupt the communication between the chamber and the passage when the pressure of air in the brake system has been reduced to a predetermined limit.

The first-mentioned member consists of a 15 valve 54 which by engagement with a seat 55 at an end of the connection 52 between the valve chamber 53 and the passage 49, obstructs the flow of air through said connection.

20 The valve is connected with an eccentric 56 on a rocker shaft 57 which at a point exteriorly of the body member on which it is rotatably mounted, has two oppositely projecting arms 58 and 59 one of which extends 25 normally in the path of the bolt 22 on the sliding member 7. Cams 155 similar to those described in connection with the valves 44 and 45, are applied to the shafts 57 to maintain by contact with springs 156, the 30 valves with which the shafts are connected in their adjusted positions.

The other member of the pressure regulating unit, consists of a valve 64 which is adapted to close the connection between the 35 chamber 53 and the passage 49 by engaging a seat 65 at the end of the same opposite to that engaged by the valve 54.

The valve 64 is normally held in a position in which it is separated from its seat 40 by the air pressure in the passage 49 which is in constant communication with the conduit 48 of the air brake system, upon a piston 66 mounted upon its stem.

The piston is movably fitted in a cylindrical recess 67 which is formed in the body member in connection with the passage 49 and which at its outer end is closed by means of a screw plug 68.

50 The plug has an axial bore through which the part of the valve stem at the opposite side of the piston projects into a cap 69 which is screwed upon the outer end of the plug.

A spring 70 coiled around the stem of the 55 valve between the piston and a shoulder on the cap, counteracts the air pressure upon the piston within the recess, and its pressure may be varied by adjustment of the cap on the plug.

60 When in the operation of the invention the valve 54 which normally closes the connection between the passage 49 and the valve chamber 53, is moved to open the said connection by the contact of the bolt 22 with 65 the arm 58 on the shaft 57, which projects in

its path, the air in the brake system, the pipe 48 of which is in constant communication with the passage 49, is permitted to enter the valve chamber and to escape through an outlet 71 of the same either directly into the 70 atmosphere or into a pipe 72 which connects with an indicating device as will hereinafter be described.

The pressure of the air in the brake system is in consequence reduced until it is less 75 than the pressure of the spring 70 upon the piston 66 when the valve 64 will be moved in engagement with its seat 65 and thereby close the connection between the air brake system and the valve chamber.

80 The springs in the different units of the series comprised in the pressure reduction system, are regulated by adjustment of the caps 69 on the respective plugs 68, so that the pressure they exert upon the respective 85 pistons, decreases progressively from the unit 60 which in the operation is first actuated by the sliding member, to the emergency unit 63 in which the spring pressure is so slight that the connection between the air- 90 brake system and the chamber is not closed until the air pressure has been diminished to the minimum required for setting the brakes:

95 When after the lower ones of the valves and reduction units of the controller element have been operated, the sliding member 7 is moved upwardly to actuate the next succeeding valves and units of the same, the arms 34 on the sliding member by engagement with the arms 46 and 58, will prevent the parts with which the latter are connected from being accidentally moved from their adjusted positions.

100 The spring in the emergency unit 63 serves to prevent the exhaust and consequent waste of air from the brake system after the unit has been operated to bring the engine to a stop.

105 The positions of the valves 44 and 45 and those of the units of the pressure reducing system are under control of the driver of the vehicle to the extent that after one or more of the valves or units have been acted upon by the operating medium, he can return the same to their normal position from the cab of the vehicle.

110 The means provided for this purpose consist of a pair of bars 73 which are slidably fitted in grooves in the body member 6 of the controller element at opposite sides of its guide way and which have pins 74 positioned to strike the arms 47 of the valves 44 and 45 and the arms 59 of the shafts 57 during upward movement of the bars.

115 The bars are suspended from bell-crank 75 which are connected with a rod 76 extending into the cab of the engine.

120 While all of the units of the reduction system and both the valves 44 and 45 can thus 130

- be simultaneously returned to their normal positions, it is preferred that the emergency unit should not be placed by these means under the control of the driver, thus requiring him to leave the cab of the locomotive to restore the valve 54 of the emergency unit to its normal position after the engine has been brought to a stop by the operation of the system.
- 10 The air from the brake system which enters the valve chambers 53 from the passage 49 in the operation of the pressure reduction system and which escapes past the valve 54 may be utilized to operate an indicator 15 preferably placed at a point in the cab of the locomotive where it can be readily observed by the driver.
- An indicator of simple construction has been shown in Fig. 7 of the drawings, and 20 its connections with the controlling element and the governor hereinafter to be described have been shown in Fig. 14.
- The indicator which in its entirety is designated by the numeral 77, comprises a number 25 of cylinders 78 which by means of the before mentioned pipes 72 are separately connected with the valve chambers 53 of the controller element.
- Pistons 79 slidably fitted in the cylinders, 30 carry at the outer ends of their rods, signaling blades 80; springs 81 within the cylinders are provided to return the pistons to their normal positions, and whistles 82 connected with the cylinders at their ends opposite to those at which the pipes 72 are attached, serve to audibly announce the operation of the respective reduction units by the exhaust of air during the return movement of the pistons.
- 40 Each cylinder is provided with a longitudinal groove 83 as shown in Fig. 13 of the drawings, to provide a passage for the air from one side of the piston to the other when after the piston has been forced outwardly 45 by the air entering the cylinder through the pipe 72, it is returned to its normal position by expansion of the spring 81.
- The cylinders are inclosed in a housing which has a number of windows 84 through 50 which the signal blades are exposed when they are moved to their indicatory positions.
- The blades are preferably provided with appropriate inscriptions to designate the units of the reduction system with which 55 they are associated.
- It will be understood from the foregoing description that the units of the pressure reducing system are relatively positioned to correspond with the relative positions of the 60 series of track devices, or in other words that the successive engagements of the operating medium with the series of track devices will effect consecutive operations of the corresponding reduction units.
- 65 The track devices are preferably placed at uniform distances from the semaphore, and the blades of the indicator 77 may be marked to denote these distances so that for example, the operation of the first unit by the engagement of the wheel on the lever 9 with the first track device, will result in exposing the blade marked "3000" in Fig. 7, thereby informing the driver of the vehicle that he has past a point "3000" feet away from a semaphore set at "danger."
- The blade of the signaling device connected with the valve chamber 53 of the emergency unit is preferably marked "Emergency" to distinguish it conspicuously from the others.
- The whistles 82 announce audibly that the reduction system has been operated and if so desired a series of differently colored electric lamps 85 may be connected in a circuit 86 with switches, designated at 87 in Fig. 7, which are closed by contact of the blades 80 or other operative parts of the indicator mechanism.
- In addition to the cylinders 78 connected with the valve chambers 53 of the recording element, a cylinder 88 is provided for the operative connection of the indicator with the automatic speed regulating element hereinafter to be described.
- The register hereinbefore referred to 95 which is inclosed in the upper compartment 20 of the case on the sliding member of the controller element, consists, briefly, of a cylinder 89 which carries upon its circumferential surface, a record sheet 90 and which receives a combined rotary and longitudinally rectilinear movement from a clock mechanism 91 which has a driving connection with a gear wheel 92 connected with the cylinder 89 by means of rods 95.
- The cylinder is provided with one or more nuts 93 by means of which it is mounted on a stationary screw 94 whereby the rotary movement it receives from the connection of the clock mechanism with the gear wheel 92, is translated into a simultaneous longitudinal movement along the screw 94.
- A pencil holder 96 movably supported upon a swinging standard 97 on the bottom of the compartment 20, is at its outer end connected with a vertically movable push-bar 98 which at its lower end carries a wheel 99. The end of the bar projects through an opening in the partition 18 between the two compartments of the case for the engagement of its wheel with the upper tapering edge of the sliding bolt 21.
- When the bolts 21 and 22 are in their retracted position as shown in Fig. 5, the one whose upper edge engages the wheel on the 125 push bar holds the latter in a raised position against the action of a spring 100 disposed between a shoulder on the bar and one of the bearings 101 in which it is slidably supported.

The pencil holder is in consequence held in a position in which its pencil 102 is separated from the surface of the record sheet on the cylinder and the latter runs idly. When, however, the bolts are projected to their operative position by means of a key inserted in the barrel 25 of the lock, the disengagement of the wheel with the upper edge of the bolt, 21 causes the spring 100 to compel 10 the bar 98 to move downwardly thereby swinging the holder 96 to the position in which its pencil engages the surface of the record sheet.

The record sheet on the cylinder is divided 15 by circumferential lines into uniform spaces 103 which are equal to the vertical displacement of the cylinder during each revolution.

The record sheet is furthermore provided with a number of vertical lines 104 which 20 divide its circumferential spaces into fractions of an hour designated in minutes, and the clock work is designed to impart a rotary movement to the cylinder at the rate of one revolution per hour.

25 It will thus be seen that the pencil while in contact with the record sheet will draw thereon a diagram showing in hours and fractions thereof, the precise time of the day during which the operative medium was in 30 an effective condition.

In addition to the devices hereinbefore described, the register includes a device for recording upon the sheet 90 the points of time at which the series of pressure reducing units are actuated by the contact of the operating medium with the series of track devices, and another device to separately record the time at which the last or emergency unit was operated by the engagement of the 40 operating medium with the highest track device adjacent the semaphore.

The two auxiliary recording devices designated in their entirety by the numerals 105 and 106, consist each of a hammer 107 fulcrumed upon a bracket 108 on the casing, as at 109, and connected by means of a pair 45 of levers 110 and 112 with a sliding push bar 113 which at its outer end has a wheel 114 projecting through a slot in the rear wall of 50 the sliding member of the controller element.

The wheel 114 is held in engagement with the surface of the guide-way 8 in the body member of the element by means of a spring 115, and the said surface has in the path of 55 the wheels on the two recording devices 105 and 106 elongate depressions 116 and 117 which correspond in their relative positions with the units of the pressure regulating system and which when during upward 60 movement of the sliding member 7 the wheels 114 enter the same, cause the respective hammers 107 to move about their fulcrums toward the surface of the cylinder 89.

The pencil holder 96 is provided at opposite 65 sides of its pencil 102 with ink-bearing

ribbons 118 of different colors which are engaged by the hammers of the two recording devices when the wheels of the same enter the respective grooves in the surface of the guide-way, it being understood that the 70 grooves 116 are positioned so that the engagement of the hammer on the lower recording device 105 with one of the ribbons on the pencil holder takes place when the bolt 22 on the operating medium has reversed the positions of the valves of the 75 first three reduction units 60, 61 and 62 by engagement with the arms 58 on their respective shafts, while the upper groove 117 is positioned so that a similar engagement 80 of the hammer of the other recording device 106 with the other ribbon on the holder occurs after the operating medium has actuated the emergency unit 63.

By the above described means, the precise 85 time at which the reductions of the air pressure in the brake system are effected, are thus permanently recorded on the sheet 90. Instead of providing ribbons of different colors to mark the impact of the hammers 90 upon the recording surface, the hammers may carry type to impress different symbols upon the same.

The appliance by which the supply of motive fluid to the propelling mechanism of 95 the power driven vehicle is discontinued when during the upward movement of the operating medium, the position of the valve 45 is reversed, is similar in construction to that described in the before mentioned application for patent.

A cylinder 119 which by means of the pipe 43 is connected with the branch 38 of the channel 35 in the controller element, has a spring pressed piston 120 the rod of 105 which connects with a lever 122 fulcrumed at 123.

The opposite end of this lever is attached to a sliding member 124 which has a loop embracing the throttle lever 125 of the locomotive. 110

When by the admission of air into the cylinder 119 the piston is moved against the pressure of its spring, the loop on the member 124 which in consequence is moved in 115 the direction of the arrow, first of all unlocks the throttle lever by engagement with a pivoted arm 126 which by means of a link 127 is connected with the pawl 128 normally engaging the teeth of the segment 129. 120

By continuing the movement of the member 124 in the same direction, the throttle lever 125 is subsequently moved to the position in which it closes the throttle valve.

The sand box 42 of the engine has as usual 125 one or two pipes 130 for discharging its contents onto the rails of the track, and it is connected by means of the before mentioned pipe 41 with the branch 37 of the channel 35 in the controller element. 130

The connection between the pipe 41 and the sand box is made by means of a branch pipe 131 of the pipe 133 which ordinarily connects the sand box with the reservoir and 5 the flow through which is controlled by a valve 132 in the cab of the engine.

When by upward movement of the sliding member of the controller element the position of the valve 44 is reversed, the air 10 entering the sand box from the reservoir 40 forcibly ejects the contents of the box through the pipe or pipes 130 onto the rails of the track.

In addition to the hereinbefore described 15 system of elements for the automatic control of the movements of a vehicle through the intermediary of devices placed adjacent the track along which the vehicle is propelled, an appliance is provided which automatically 20 produces a similar effect when the speed of the vehicle exceeds a predetermined and variable limit.

This appliance consists as shown in Fig. 14 of the drawings, of a centrifugal governor 134 which by means of two gears 135 and 136 is operatively connected with a rotary axle 137 of the locomotive.

The governor is connected with a follower 138 which when by an excess in the velocity 30 of the part 137 the balls of the governor are moved centrifugally outwardly, engages spring controlled valves 139 and 140 in pipes 141 and 142, one of which connects with the before-mentioned pipe 48 of the air-brake system and the other one of which connects the reservoir 40 with the cylinder 119 of the throttle closing appliance and with the pipe 131 between the controller element and the sand box.

40 A pipe 143 leads from the pipe 141 to the cylinder 88 of the indicator 77 hereinbefore referred to, the blade on the piston of the cylinder being preferably marked "Excess" as shown in Fig. 7 of the drawings.

45 The movements of the follower 138 are restricted by means of a pair of springs 144 which at one of their ends are connected to the follower and at their opposite ends to a plate 145 which is adjustably mounted 50 upon a stationary part 146 of the vehicle.

The latter is to this end provided with a screw 147 upon which the plate 145 is loosely supported between two nuts 148 and 149.

55 By adjustment of these nuts the tension of the springs 144 may be increased or decreased in accordance with the angular velocity of the shaft 137 at which it is desired to open the valves 139 and 140.

60 Check valves 150 in the pipes 41 and 142 at opposite sides of the branch pipe 131 which connects with the sand box 42 are provided to prevent the flow of air past the branch pipe in either direction when air is 65 admitted into the pipe 41 past the valve 44

on the controller element or past the valve 140 of the automatic speed limiting appliance.

From the foregoing description the operation of my invention will be readily understood. 70

Each series of track devices connected with the semaphore are positioned forward of the same with relation to the predetermined direction in which the vehicle is propelled along the track, in consecutive order 75 and at substantially uniform distances apart.

When the semaphore is adjusted to its danger indicating position, the track devices are at the same time rendered effective for 80 the operation of the elements of the automatic movement controlling mechanism carried on the vehicle.

The apexes of the rails on the series of track devices are disposed at progressively 85 increasing elevations from the device farthest away from the semaphore to that most adjacent thereto.

The differences in the elevations of the apexes of the rails are proportionate to the 90 distances between the rotary shafts of the units of the pressure reducing system on the controller element, so that when the wheel on the operating medium rides successively to the apexes of the rails on the track devices, the medium will in consecutive order 95 actuate the units and thereby effect a gradual reduction of the air pressure in the brake system of the engine and the train attached thereto.

100 The actuation of the emergency unit which exhausts the air from the brake system to a degree sufficient to firmly set the brakes, is resorted to only in case of extreme danger, and in the ordinary operation of the system the engineer after having been warned by means of the indicator, of the approach of the engine toward a semaphore set at danger, knows that a reduction in the air pressure of the brake system has already 105 been automatically effected, and if at all capable he will be able to control the further movements of the locomotive so as to avoid disobedience of the track rules and consequent accidents without further aid of the 110 automatic movement controlling system.

115 It will be seen, however, that in any case even when the brakes are set by the operation of the automatic brake system, the pressure of air in the brake system is reduced 120 gradually and that by virtue of this feature in the operating, damage to the rolling stock by sudden stoppage, and accidents likely to occur by the same cause, are effectively averted.

125 The operating medium composed of the sliding member of the controller element and the spring-held lever, may be rendered effective or ineffective at the will of the driver of the engine or an official of the 130

railroad, by adjustment of the bolts on the sliding member by means of a key inserted in the lock with which they are operatively associated.

5 The periods during which the operating medium is in an effective condition are recorded on the sheet of the register in the case on the sliding member of the controlling element, which after the clock mechanism 10 has been wound, is locked by an official of the railroad. The driver of the vehicle is thus compelled to maintain the operating medium in an effective condition in accordance with instructions, and in case of failure 15 to stop at a danger indicating signal, cannot lay the blame on the automatic movement controlling mechanism, inasmuch as the record sheet of the registering device will indicate the precise periods during which the 20 said mechanism was in operative condition.

When the wheel on the lever of the operating medium acting intermittently of the track devices and the controller element, rides to the apex of the rail on the first track device 25 in the series encountered by the vehicle as it approaches a semaphore set at danger, it actuates the first unit of the pressure reducing system on the said element and thereby reduces the air pressure in the brake system 30 to a degree of density determined by the pressure exerted by the spring of the unit. Upon engagement of the wheel on the operating medium with the rail of the second track device in the series, the air pressure 35 is still further reduced and in this manner the air pressure is gradually lowered and the speed of the vehicle proportionately reduced. Upon contact of the wheel with the last of the series of track devices, nearest 40 the semaphore, the emergency unit is actuated when the locomotive is brought to an emergency stop.

Before the emergency unit is operated by the upward movement of the sliding member 45 of the controller element, the cylinder of the throttle closing appliance and the sand box have been automatically placed in communication with the air-reservoir by movement of the valves 44 and 45 and the supply of 50 motive fluid to the propelling mechanism of the engine is in consequence discontinued while sand is applied to the rails to prevent the wheels from sliding.

In this connection I desire it understood 55 that while the valves 44 and 45 have been shown in the drawings as being positioned in alignment with the first and second units of the pressure reducing system, they may be located at any other point including a 60 point at which the actuation of the emergency unit is accomplished.

The engineer can at any time after one or more of the pressure reducing units have been actuated, return the parts to their nor-

mal position by manipulation of the rod 76 65 which connects with the slides on the controller element, but to restore the emergency unit to its normal condition after the vehicle has been brought to a stop, he is compelled to leave the vehicle. 70

The different actions taking place in the controller element as well as the distances from the semaphore at which they occurred, are communicated to the driver by the indicator, the whistles connected with the cylinders thereof, and the electric lamps, it being understood that as many indicatory devices may be provided as are required to acquaint both the engineer and the fireman of a locomotive with the conditions in the 80 operation of the automatic system.

The governor after having been adjusted to the maximum speed at which it is desired to run the vehicle, automatically effects a 85 gradual reduction of the air pressure in the air brake system and at the same time discontinues the supply of motive fluid to the propelling mechanism of the vehicle and causes a discharge of sand onto the rails by placing the sand box and the cylinder of 90 the throttle closing appliance in communication with the reservoir.

After the speed of the vehicle has been reduced to the predetermined limit, the governor by releasing the valves 139 and 140 95 causes them to close by the action of their respective springs and thereby releases the brakes and discontinues the discharge of sand onto the rails.

It will be understood that if it is desired 100 to operate the automatic movement controlling system during backward movement of the locomotive, a controller element and an operating medium, identical to those hereinbefore described, are placed at the opposite side of the vehicle to engage track devices placed on the opposite side of the track.

Having thus described my invention what I claim and desire to secure by Letters-Pat- 110 ent is:

1. In a system of the character described, the combination with an air brake system of a power-driven vehicle, of a plurality of valve-units separately connected in an air-brake system and adapted to reduce the 115 pressure therein to different predetermined degrees, and a medium carried on the vehicle for the successive operation of said units, by contact with a series of devices placed in its path at distances apart which 120 relatively are in ratio to the spaces between the said units.

2. In a system of the character described, the combination with an air-brake system of a power-driven vehicle, of a controller element on the vehicle, for the gradual reduction of the normal air-pressure in the air-brake system, comprising a series of units 125

each including two coöperative members one of which is adapted to effect a discharge of air from the air brake system, and the other one of which operates to discontinue said discharge when the air pressure is reduced to a predetermined degree, and a medium carried on the vehicle for the successive operation of the first mentioned members of the units by contact with devices placed in 10 its path.

3. In a system of the character described, the combination with an air-brake system of a power-driven vehicle, of a controller-element on the vehicle, for the gradual reduction of the normal air-pressure in the air-brake system, comprising a series of units each adapted to operate for effecting a discharge of air from the air-brake system until its pressure is reduced to a predetermined degree; the said element having outlets for the separate discharge of air from the air-brake system in the operation of each of said units, a medium carried on the vehicle, for the successive operation of said units by contact with devices placed in its path, and an indicator for denoting the operation of the element at a point remote therefrom, including a series of indicator devices adapted to operate by air pressure 25 and connected respectively with the said outlets.

4. In a system of the character described, the combination with an air-brake system of a power-driven vehicle, of a controller element on the vehicle, for the gradual reduction of the normal air-pressure in the air-brake system, comprising a series of units each adapted to operate for effecting a discharge of air from the air-brake system until its pressure is reduced to a predetermined degree, the said element having outlets for the separate discharge of air from the air-brake system in the operation of each of said units, a medium carried on the vehicle, for the successive operation of said units by contact with devices placed in its path, and an indicator for denoting the operation of the element at a point remote therefrom, including a series of audible signaling devices connected respectively with the said outlets and adapted to be sounded by an air-current passing through them.

5. In a system of the character described, the combination with an air-brake system of a power-driven vehicle, of a controller element on the vehicle for the gradual reduction of the normal air-pressure in the air-brake system, including a passage in connection with the air-brake system, ducts for the discharge of air from said passage at different points thereof, a series of reduction units controlling the flow of air through said ducts, each including a valve which normally closes the respective duct and a sec-

ond valve capable of closing the same duct 65 after it has been opened by operation of the other valve, by an overbalance of pressure due to a decrease in air-pressure in the passage, and a medium carried on the vehicle for the successive operation of the first-mentioned valves of the series of units, by contact with devices placed in its path.

6. In a system of the character described, the combination with an air-brake system of a power-driven vehicle, of a controller 75 element on the vehicle, for the gradual reduction of the normal air-pressure in the air-brake system, including a passage in connection with the air-brake system, ducts for the discharge of air from said passage at 80 different points thereof, a series of reduction units controlling the flow of air through said ducts, each including a valve which normally closes the respective duct, a second valve capable of closing the same duct after 85 it has been opened by operation of the other valve, by an overbalance of pressure due to a decrease in air pressure in the passage, and means for regulating the operating pressure on the second valve, and a medium 90 carried on the vehicle, for the successive operation of the first-mentioned valves of the series of units, by contact with devices placed in its path.

7. In a system of the character described, 95 the combination with an air-brake system of a power-driven vehicle, of a controller element including a duct for the discharge of air from the air-brake system, and a piston chamber in connection with said duct, a valve normally closing said duct, a second valve adapted to close the duct after it has been opened by operation of the other valve, a piston in the piston chamber, in connection with the second valve, exposed to the pressure of air in the air-brake system at one side and subjected to a different pressure at its opposite side, whereby it is moved to close the duct by means of the second valve when the pressure in the air-brake system is 100 reduced to a predetermined degree, and a medium for operating the first-mentioned valve.

8. In a system of the character described, 115 the combination with an air-brake system of a power-driven vehicle, of a controller element including a duct for the discharge of air from the air-brake system, and a piston chamber in connection with said duct, a valve normally closing said duct, a second 120 valve adapted to close the duct after it has been opened by operation of the other valve, a piston in the piston chamber, in connection with the second valve, exposed to the pressure of air in the air-brake system at one side and subjected to a different pressure at its opposite side, whereby it is moved to close the duct by means of the second 125

valve when the pressure in the air-brake system is reduced to a predetermined degree, means for regulating the operative pressure on the piston, and a medium for operating 5 the first-mentioned valve.

9. In a system of the character described, the combination with an air-brake system of a power-driven vehicle, of a controller element including a duct for the discharge of 10 air from the air-brake system, and a piston chamber in connection with said duct, a valve normally closing said duct, a second valve adapted to close the duct after it has been opened by operation of the other valve, 15 a piston in the piston chamber, in connection with the second valve, exposed to the pressure of air in the air brake-system at one side, a spring bearing upon the opposite side of the piston for moving it to close the duct, 20 by means of the second valve when the pressure in the air-brake system is reduced to a predetermined degree, and a medium for operating the first-mentioned valve.

10. In a system of the character described, 25 the combination with an air-brake system of a power-driven vehicle, of a controller element including a duct for the discharge of air from the air-brake system, and a piston chamber in connection with said duct, a valve normally closing said duct, a second valve adapted to close the duct after it has been opened by operation of the other valve, a piston in the piston chamber, in connection with the second valve, exposed to the 30 pressure of air in the air brake-system at one side, a spring bearing upon the opposite side of the piston for moving it to close the duct by means of the second valve when the pressure in the air-brake system is reduced 35 to a predetermined degree, means for regulating the pressure exerted by the spring, and a medium for operating the first-mentioned valve.

11. In a system of the character described, 40 the combination with an air-brake system of a power driven vehicle, of a controller element for the gradual reduction of air pressure in the brake system, including a series of successive reduction units each including a valve capable of operation to effect an escape of air from the air-brake system, and a second valve capable of operation by an overbalancing pressure to discontinue the 45 said escape when the pressure of air in the brake system has been reduced to a predetermined degree, the operative pressures on the second valves in the series of successive units decreasing progressively, and a medium on the vehicle, for successively operating the first mentioned valves of the series 50 of units.

12. In a system of the character described, 55 the combination with an air-brake system of a motor driven vehicle, an appliance for discontinuing the supply of motive fluid to

the propelling mechanism of the vehicle and a sand-box on the vehicle, of a source of fluid-supply, a controller-element including a connection between said source and said appliance, a connection between the source and the sand-box, means for effecting a reduction in the air-pressure in the brake-system, and automatic valves normally closing said connections, a medium for operating said means and opening said valves, by contact with an element placed in its path, a governor connected to be driven from a rotary part of the vehicle, a secondary valve connected in the brake system for the escape of air therefrom, secondary connections between said source, said appliance and the sand box, a secondary valve in said secondary connections, and a contrivance actuated by the governor when the velocity of the said rotary part of the vehicle exceeds a predetermined limit, for opening said secondary valves.

13. In a system of the character described, the combination with an air-brake system of a motor-driven vehicle, an appliance for discontinuing the supply of motive fluid to the propelling mechanism of the vehicle, a source of fluid-supply, a controller element including a connection between said source and said appliance, means for effecting a reduction in the air-pressure in the brake-system, and a valve normally closing said connection, a medium for operating said means and opening said valve by contact with an element placed in its path, a governor connected to be driven from a rotary part of the vehicle, a secondary valve connected in the brake-system for the escape of air therefrom, a secondary connection between the source and the appliance, a secondary valve in the said secondary connection, and a contrivance actuated by the governor when the velocity of the said rotary part of the vehicle exceeds a predetermined limit, for opening said secondary valves.

14. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including a lever fulcrumed at one of its ends on the vehicle, a member adjacent the opposite end of the lever for contact with said element, and a reciprocating member connected with the lever at an intermediate point, for engagement with said means.

15. In a system of the character described, the combination with movement-controlling mechanism of a power-driven vehicle, of means for automatically effecting an operation of said mechanism to reduce the speed

of the vehicle, a slotted arm fixed on the vehicle, and an operating medium carried on the vehicle for the actuation of said means by contact with an element placed in its path, including a lever fulcrumed at one of its ends on the vehicle, and having at its opposite end a pin which travels in the slot of said arm, a member on the lever adjacent its last-mentioned end for contact with said element, and a reciprocating member connected with the lever at an intermediate point, for engagement with said means.

16. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member, a projectable bolt on said member to operatively engage a part of said means extending in its path, and a device for the projection and retraction of said bolt.

17. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member, a projectable bolt on said member to operatively engage a part of said means extending in its path, and a key-controlled device for the projection and retraction of said bolt.

18. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member, a projectable bolt on said member to operatively engage a part of said means extending in its path, and a key-controlled mechanism for the projection and retraction of said bolt, including means for locking it in its adjusted positions.

19. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member, a plurality of projectable bolts on

said member to operatively engage parts of said means extending in their paths, and a device for the simultaneous projection and retraction of said bolts.

20. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member, a plurality of projectable bolts on said member to operatively engage parts of said means extending in their paths, and a key-controlled device for the simultaneous projection and retraction of said bolts.

21. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member having a working part capable of being placed in effective and ineffective conditions, and key-controlled mechanism for placing said part in either condition.

22. In a system of the character described, the combination with movement-controlling mechanism of a power-driven vehicle, of means for automatically effecting an operation of said mechanism to reduce the speed of the vehicle, and an operating medium carried on the vehicle for the actuation of said means by contact with an element placed in its path, including an operative member having a working part capable of being placed in effective and ineffective conditions, and key-controlled mechanism for placing and locking said part in either condition.

23. In a system of the character described, the combination with movement-controlling mechanism of a power driven vehicle, of means for effecting an operation of said mechanism to reduce the speed of the vehicle, including a rotatable device having laterally projecting arms, a medium on the vehicle for the operation of said means by contact with an element placed in its path, including an operating member having a projection for engagement with one of said arms to operate the said device, and means for returning the device to its original position from a point remote therefrom, including an operating member having a projection to engage the other arm.

24. In a system of the character described, the combination with movement controlling mechanism of a power-driven vehicle, of a controller element including a plurality

of devices which coöperate to effect an operation of said mechanism to reduce the speed of the vehicle, a medium carried on the vehicle for the operation of said devices by contact with an element placed in its path, and means for returning said devices to their original condition including a reciprocating member and means for the operation of said member from a point remote therefrom, the said member and the said devices having coöperative means for returning the devices to their original position by a determinate movement of the said member, after they have been operated by action of the said medium.

25. In a system of the character described, the combination with an air-brake system of a power-driven vehicle, of a plurality of valve-units separately connected therein and adapted to respectively reduce the air-pressure in the system to different predetermined degrees by the escape of air therefrom, a medium carried on the vehicle to successively operate said units by contact with elements placed in its path, and an indicator-element connected with said units and capable of different distinctive actions by the escape of air in the operation of the same, whereby to separately indicate the operation of each unit at a point remote therefrom.

26. In a system of the character described, the combination with an air-brake system of a power-driven vehicle, of apparatus adapted to produce a gradual reduction of air-pressure therein by a series of intermittent actions which effect an escape of air from the system to different predetermined degrees, and an indicator-element connected with said pressure-reducing apparatus and capable of different distinctive actions by the escape of air in the operation of the same, whereby to separately indicate the actions of the pressure-reducing apparatus at a point remote therefrom.

27. In a system of the character described, the combination with an air-brake system of a power-driven vehicle, of a plurality of valve-units separately connected therein and adapted to respectively reduce the air-pressure in the system, to different predetermined degrees by the escape of air therefrom, and a medium carried on the vehicle for the successive operation of said units by contact with a number of devices placed correspondingly in its path.

28. In a system of the character described, the combination with movement-controlling mechanism of a power-driven vehicle, of a medium adjustable to operative and inoperative positions, and adapted for the automatic regulation of said mechanism, and registering mechanism in coöoperative connection with said medium and adapted to record the lengths of periods during which

the latter is in its adjusted operative position.

29. In a system of the character described, the combination with movement-controlling mechanism of a power-driven vehicle, of a medium adapted for the automatic regulation of said mechanism, including a reciprocating member, a projectable bolt on said member to operatively engage a part of said mechanism, and means for the projection and retraction of said bolt, and a register in coöoperative connection with said bolt, and adapted to record the periods during which it is in its projecting position.

30. In a system of the character described, the combination with movement-controlling mechanism of a power-driven vehicle, of a medium adapted for the automatic regulation of said mechanism, including a reciprocating member, a projectable bolt on said member to operatively engage a part of said mechanism, and means for the projection and retraction of said bolt, and a register in coöoperative connection with said bolt, and adapted to record the periods during which it is in its projecting position, said register including a rotary record-receiving surface and a device for recording on said surface, which is separated from the recording surface when the bolt is in its retracted position and which is adapted to be moved into engagement with said surface by movement of the bolt to its projecting position.

31. In a system of the character described, the combination with an air-brake system of a power-driven vehicle, of a plurality of valve-units separately connected therein and adapted to respectively reduce the air-pressure in the system, to different predetermined degrees by the escape of air therefrom, an indicator adapted to separately indicate the operations of said units at a point remote therefrom, means for transmitting the operative movements of said units to said indicator, and a medium carried on the vehicle to successively operate said units by contact with an element placed in its path.

32. In a system of the character described, the combination with an air-brake system of a power-driven vehicle, of a plurality of valve-units separately connected therein and adapted to respectively reduce the air-pressure in the system, to different predetermined degrees, by the escape of air therefrom, an indicator adapted to separately indicate the operations of said units at a point remote therefrom, by fluid pressure, conduits for admitting air escaping from the brake system by operation of said units, to said indicator, and a medium carried on the vehicle to successively operate said units by contact with an element placed in its path.

33. In a system of the character de-

- scribed, the combination with an air-brake system of a power-driven vehicle, of a plurality of valve-units separately connected therein and adapted to respectively reduce 5 the air-pressure in the system to different predetermined degrees, by the escape of air therefrom, an operating medium on the vehicle for the successive operation of said units, by contact with an element placed in 10 its path, and a register co-operatively connected with said medium and adapted to record the point of time at which each unit is operated thereby.
34. In a system of the character de- 15 scribed, the combination with an air-brake system of a power-driven vehicle, of an appliance adapted to gradually reduce the air-pressure in the system by a succession of intermittent operations, a source of fluid- 20 pressure separate from the air-brake system, fluid-impelled means for discontinuing the supply of motive fluid to the propelling mechanism of the vehicle, in connection with said source, a valve in said connection, and 25 an operating medium adapted for the operation of said appliance to gradually reduce the pressure in the air-brake system, and for the adjustment of said valve to an open position, in an early part of said pressure- 30 reducing operation of the appliance.
35. In a system of the character de- 35 scribed, the combination with an air-brake system of a power-driven vehicle, of an appliance adapted to gradually reduce the air-pressure in the system by a succession of intermittent operations, a source of fluid-pressure separate from the air-brake system,
- fluid-impelled means for discontinuing the supply of motive-fluid to the propelling mechanism of the vehicle, in connection with said source, a sand-box on the vehicle, in connection with said source, valves controlling said connections, and an operating medium adapted for the operation of said appliance to gradually reduce the pressure in the air-brake system, and for opening said valves in an early part of said pressure-reducing operation of the appliance, to connect said source of motive-fluid supply with the sand-box and with said fluid-impelled means. 40
36. In a system of the character de- 45 scribed, the combination with an air-brake system of a power-driven vehicle, of an appliance adapted to gradually reduce the air-pressure in the system by a succession of intermittent operations, fluid-impelled means for discontinuing the supply of motive-fluid to the propelling mechanism of the vehicle, a valve controlling the supply of motive 50 fluid to said fluid impelled means, and an operating medium adapted for the operation of said appliance to gradually reduce the pressure in the air-brake system, and for the adjustment of said valve to an open position, 55 in an early part of said pressure-reducing 60 operation of the appliance.

In testimony whereof I have affixed my signature in presence of two witnesses.

JAMES CULTON.
